B. E. MUSSER

CLOTHES WASHING EQUIPMENT

Filed March 27, 1924

Patented Oct. 6, 1925.

1,556,243

UNITED STATES PATENT OFFICE.

BENJAMIN E. MUSSER, OF BELLINGHAM, WASHINGTON.

CLOTHES-WASHING EQUIPMENT.

Application filed March 27, 1924. Serial No. 702,401.

To all whom it may concern:

Be it known that I, BENJAMIN E. MUSSER, a citizen of the United States, residing at Bellingham, in the county of Whatcom and 5 State of Washington, have invented certain new and useful Improvements in Clothes-Washing Equipment; and I do declare the following to be a full, clear, and exact description of the invention, such as will enable others skilled in the art to which it 10 appertains to make and use the same.

My invention relates to improvements in clothes washing equipment comprising a tub and an ordinary washboard. Heretofore, 15 numerous devices have been provided, carried by the washboard and engageable with the tub, in attempts to hold them against relative movements when they are in use. Other attempts have been made to obtain 20 the same result by providing attachments on the tub to engage the washboard, but for one reason or another, these prior devices have proven more or less impractical and have never come into general use. It 25 is the object of my invention however to provide the tub and board with unique co-acting means of extremely simple and inexpensive form, yet capable of obtaining the desired results, without the use of positive 30 connections, such as clamps, between the washboard and tub.

With the foregoing in view, the invention resides in the novel subject matter herein-after described and claimed, the description 35 being supplemented by the accompanying drawing.

Figure 1 is a vertical sectional view.

Figure 2 is a similar view on line 2-2 of Fig. 1.

Figure 3 is a fragmentary plan view.

In the drawing above briefly described, the numeral 1 designates a metal wash-tub having a bead 2 around its upper edge. Immediately below this bead, at one side of the 45 tub wall, I provide a pair of spaced openings 3 which extend entirely through said wall.

The numeral 4 designates an ordinary washboard adapted to assume the usual inclined position in the tub 1, and I provide the two side members of said board with 50 upper and lower projections 5 and 6 which are preferably of different lengths, the projections 5 being adapted to rest upon the bead 2, while the projections 6 pass outwardly through the slots 3. By this arrangement 55

of co-acting means on the tub and washboard, I hold the latter against vertical sliding as well as horizontal sliding, and provide an exceptionally simple and inexpensive 60 structure, which does not in any manner interfere with quick and easy removal of the board from the tub.

In the preferred form of construction, each pair of projections 5 and 6 is formed of a single short length of stiff wire. This wire is bent at its intermediate portion in the form of an arch 7 to straddle the bead 2, and after forming the legs of the arch, the end portions of the wire are bent outwardly substantially upon themselves to provide attaching arms 8 which project beyond the crown portion of said arch, the ends of said arms being bent laterally as indicated at 9 to form trunnions which are 70 received in staples 10 driven into the side members of the board 4, or in other appropriate bearing eyes. The trunnions 9 preferably extend inwardly toward each other as shown and I prefer that they be located 75 on substantially the longitudinal centers of the side members of the washboard so that the bent wires may be swung to either side of the latter, permitting said washboard to be reversed in the usual manner. It will 80 be seen that the portions of the wire at the juncture of the arch 7 with the arms 8, form the upper and lower projections 5 and 6.

As excellent results may be obtained from the details disclosed, and such details are 85 exceptionally simple and inexpensive, they are preferably followed, but within the scope of the invention as claimed, minor changes may be made.

I claim:

1. In combination, a wash tub having a bead at its upper edge and a pair of horizontally spaced openings under said bead, a washboard adapted to assume the usual inclined position in the tub, and pairs of spaced projections extending downwardly from said washboard to straddle said bead and hold the board against vertical sliding, the lowermost of said projections being adapted to extend outwardly through said openings to hold said board against lateral sliding.

2. A wash board attachment comprising a short length of wire bent at its intermediate portion to provide an arch whose crown is adapted to rest on a bead at the upper edge of a wash tub, the wire ends after form-

ing the legs of said arch being bent upon themselves to provide attaching arms, said arms being extended beyond the crown of the arch and having their ends bent laterally to provide trunnions for connecting said arms to a wash board.

3. In combination, a wash tub having a bead at its upper edge and a pair of horizontally spaced openings, the upper edges

of which are formed by said bead, a wash board and means carried by said board adapted for insertion through said openings and engagement with said bead to hold said board against lateral sliding movement.

In testimony whereof I have hereunto af-
fixed my signature.

BENJAMIN E. MUSSER.
